UNITED STATES PATENT OFFICE.

GEORGE D. SMITH, OF BICKNELL, INDIANA.

ROPE OR CABLE LUBRICATOR.

1,102,965.

Specification of Letters Patent.

Patented July 7, 1914.

Application filed March 4, 1914. Serial No. 822,486.

To all whom it may concern:

Be it known that I, GEORGE D. SMITH, a citizen of the United States, residing at Bicknell, in the county of Knox and State 5 of Indiana, have invented new and useful Improvements in Rope or Cable Lubricators, of which the following is a specification.

This invention relates to a rope or cable lubricator, and particularly to a device for 10 oiling or lubricating hoisting ropes or cables, such as are used in connection with hoisting apparatus at coal mines, etc., and which in use are subjected to considerable friction, wear and tear.

15 The object of the invention is to provide a simple, convenient, reliable and efficient device for the purpose stated, which may be readily applied to the rope or cable for the purpose of lubricating the same and as 20 readily removed therefrom after the rope or cable has been lubricated to the desired degree.

25 The invention consists of the features of construction, combination and arrangement 25 of parts herein fully described and claimed, reference being had to the accompanying drawing in which:—

30 Figure 1 is a view of a rope or cable lubricator embodying my invention. Fig. 2 is a vertical longitudinal section thereof. Fig. 3 is a horizontal transverse section on the line 3—3 of Fig. 2. Fig. 4 is a detail view showing the closure slide.

35 In carrying my invention into practice, I provide a vessel or reservoir 1, preferably of conical form, and provided at its top with diametrically disposed handles 2 by which it may be conveniently transported and hung up when not in use. The body of the vessel 40 is provided with fastening straps 3 adapted for engagement with buckles 4, which straps are designed for securing the device to a suitable support when in use to lubricate a rope or cable.

45 The lower contracted end of the conical vessel is open for the passage of the rope or cable 5, and extending longitudinally at one side of the vessel, between its upper and lower edges is a slot 6, designed to permit the 50 device to be applied to and removed from the cable by a relative lateral movement, in which the cable passes into and out of the vessel through the slot 6. Within the vessel is a body of suitable absorbent material 55 7, such as waste, saturated with the oil or

lubricant which is to be applied to the rope or cable.

The walls of the slots 6 are bent to form 60 guide ways 8 to receive a sliding closure member 9, the edges of which slidably engage the said guide ways. This closure member 9 is provided at its upper end with a suitable manipulating handle 10, and said closure member is designed and adapted in practice to be removed to permit of the entrance of the rope or cable through the slot 6 when the device is applied for use, and then to be inserted in place to close the slot and hold the vessel and cable against relative 65 displacement. It will be understood, of course, that the rope or cable when applied may be lubricated by either moving the device along the rope or cable or moving the cable through the device, and conveniently the device may be employed by supporting 70 it in a stationary position and allowing the cable to run therethrough while it is in working action. By the provision of the slot 6 it will be evident that the lubricator may be quickly and conveniently applied 75 and detached, and that the closure member 9 will hold the cable from displacement while the lubricator is in working position thereon. By means of the present invention the operation of lubricating a rope or cable which is 80 subjected to friction, wear and tear may be readily and conveniently performed at intervals, the lubrication of the cable increasing 85 its period of usefulness by reduction of friction and wear, as will be readily understood.

I claim:—

1. A rope or cable lubricator comprising a conical vessel provided with lubricating means therein, said vessel having at one side 90 a longitudinally extending slot, whereby it is adapted to be applied by relative lateral motion to and from the cable, a member for slidably engagement with the vessel adapted to close said slot, and means for holding the 100 vessel contracted to dispose the walls of the slot for engagement with said closure member, said means being adapted for securing the vessel to a suitable support.

2. A rope or cable lubricator comprising 105 a conical vessel containing lubricating means and formed of a single piece of resilient material, said vessel being provided at one side thereof with a longitudinal slot and guide-ways at opposite sides thereof, a closure 110

plate engageable with said guideways, and means for holding the vessel contracted and securing the same to a support.

3. A device for lubricating ropes or cables comprising a conical vessel provided with lubricating means therein, said vessel being formed in one of its sides with a longitudinally extending slot, said slot having rigid walls bent to form guide ways, a closure member adapted for sliding engagement

with said guide ways and extending the length thereof to close said slot and means for securing the container to a support.

In testimony whereof I affix my signature in presence of two witnesses.

GEORGE D. SMITH.
